US0D1109906S

(12) **United States Design Patent** (10) Patent No.: **US D1,109,906 S**
(45) Date of Patent: ** Jan. 20, 2026

(54) **CENTER POSITION LAMP FOR AUTOMOBILE**

(71) Applicants: **HYUNDAI MOTOR COMPANY**, Seoul (KR); **Kia Corporation**, Seoul (KR)

(72) Inventors: **Young Hwan Shin**, Seongnam-si (KR); **Chung Eun Kim**, Seoul (KR)

(**) Term: **15 Years**

(21) Appl. No.: **35/518,963**

(22) Filed: **Oct. 6, 2023**

(80) **Hague Agreement Data**

Int. Filing Date: **Oct. 6, 2023**

Int. Reg. No.: **DM/232818**

Int. Reg. Date: **Oct. 6, 2023**

Int. Reg. Pub. Date: **Nov. 10, 2023**

(30) **Foreign Application Priority Data**

Jun. 30, 2023 (KR) 30-2023-0025241

(51) **LOC (15) Cl.** **26-06**

(57) **CLAIM**

The ornamental design for a center position lamp for automobile as shown and described.

DESCRIPTION

1. Center position lamp for automobile

1.1 : Perspective

1.2 : Front

1.3 : Back

1.4 : Left

1.5 : Right

1.6 : Top

1.7 : Bottom

1.8 : Bottom Perspective

1.9 : Rear Perspective

1 Claim, 9 Drawing Sheets
